UNITED STATES PATENT OFFICE.

RICHARD CADWALADR ROBERTS, OF WYMEWSWOLD, ENGLAND.

TRIM-INDICATOR FOR SHIPS.

1,110,347.

Specification of Letters Patent. Patented Sept. 15, 1914.

Application filed September 10, 1913. Serial No. 789,105.

To all whom it may concern:

Be it known that I, RICHARD CADWALADR ROBERTS, a subject of the King of Great Britain, and a resident of Wymeswold, 5 Leicestershire, in England, have invented a certain new and useful Improved Trim-Indicator for Ships, of which the following is a specification.

This invention relates to improvements in 10 trim indicators for ships of the kind in which a pendulum or the like is suspended in or on a frame, and means are provided for exactly indicating the position of the former relatively to the latter.

15 Referring to the drawings, Figure 1. is a perspective view of a trim indicator constructed according to my invention, showing the tilting mirror removed. Fig. 2. is a perspective view of the main framing of the 20 indicator, and Fig. 3. a vertical section showing the tilting mirror in position.

Like letters indicate like parts throughout the drawings.

According to this invention, the main part 25 of the indicator consists of a skeleton frame A, provided at the base with leveling screws B, which may also serve to secure it to a solid platform or framing on the ship. Suspended within this frame is a lever C. D. 30 (see Fig. 1.) the main dependent member C of which is provided at its lower end with a heavy weight or bob E. The lever described is provided with two suspension heads C', which are situated some distance apart and 35 are adapted to rest on horizontal knife edge fulcrums F (see Fig. 2.) secured to the respective sides of the upper part of the main frame A, so that said lever can swing freely in a vertical plane. The other member D 40 of the weighted lever described, extends approximately in a horizontal direction, and its free end D¹ is carried up through an opening G in the upper part of the main framing A, and terminates in a plane surface which is approximately horizontal and 45 level with the upper surface of the said frame A, when the lever is at zero.

In the construction shown in the drawings, the upper end of the main member C of 50 the weighted lever C D is divided, and the member D is formed by branches from the said divided upper end of C, and a single branch from its lower end all united at the free end D¹, providing a lever construction

which is not materially deflected by strains 55 or changes in temperature. As the weighted lever C D will owing to the action of gravity, always maintain the same position in space, any movement of the main frame A relatively thereto will be indicated by a 60 movement of the free end D¹ of the member D relatively to the upper surface of said frame, and this is indicated to an amplified extent on a fixed scale on the framing, by an optical system arranged as follows:— 65

An approximately vertical mirror H (see Fig. 3.) is carried on a base J provided with say three legs J¹ J², and this mirror H is placed with two of its legs J¹, resting on the upper surface of the framing A, and the 70 remaining leg J² resting on the plane surface at the free end D¹ of the member D of the lever C. D. Any movement of the latter relatively to the main frame A thus serves to tilt the mirror H either one way or the 75 other. To prevent displacement of the mirror H, the lower ends of the legs J¹ J², are pointed, and small recesses M (see Fig. 1.) are provided for them in the upper surface of the framing A, and the free end D¹ of the 80 lever C D respectively.

On the frame A opposite to the mirror H, is a vertical scale K (see Fig. 1.) and at the side of the scale is a telescope L fitted with a cross wire. The several parts are so disposed that an image of the scale K is seen in the mirror H by looking through the telescope L, and the position of the cross wire in the latter as seen in relation to the scale, is determined by the inclination of the mirror H, which arrangement indicates to a 85 very much amplified extent, any movement of the weighted lever C D relatively to the 90 frame A.

In use the indicator is placed on a firm 95 platform or framing in any convenient part of the ship, and it is set so that the weighted lever C D moves in a direction which is exactly fore and aft of the vessel. It is then when the ship is trim, leveled carefully by 100 the screws provided for this purpose until the cross wire in the telescope registers with zero in the middle of the scale K. This leveling may be done once and for all on a favorable occasion when it is known that the ship is exactly trim. At any subsequent time, the trim of the ship can be obtained by simply taking the reading from the scale 105

K and multiplying that reading by a factor which is peculiar to and constant for that particular ship, and is supplied with the instrument.

5 The advantages of the instrument are many, it is compact, strong, works automatically, and it is not liable to get out of order. The great magnification of the primary motion which is obtained by using a tilting 10 mirror, telescope, and scale, is not obtained at the expense of accuracy, as the amplification is obtained by the reflection of light, and not by the multiplication of moving parts. Its immense sensitiveness is exemplified in the fact that a scale division which 15 will indicate an inclination of one in six thousand can be easily read.

What I claim as my invention and desire to cover by Letters Patent is:—

20 1. In a trim indicator, the combination, with a frame adapted to partake of the motion of the ship, of a lever pivotally supported by the frame, a weight which holds the lever relatively stationary in the frame, 25 and an oscillatory indicating mirror pivotally supported between the said lever and frame.

2. In a trim indicator for ships, the combination of a framing, a weighted lever suspended in or on said frame, and optical indicator mechanism with a mirror which is connected to and tilted by a movement of the lever relatively to the frame, substantially 30 as described.

35 3. In a trim indicator for ships, the combination of a framing, a weighted lever suspended in or on said frame, a fixed scale, and optical indicator mechanism consisting of a telescope with a cross wire, and a mir-

ror which is connected to and tilted by a 40 movement of the lever relatively to the frame, substantially as described.

4. In a trim indicator for ships, the combination of a framing, a weighted lever suspended in or on said frame, a mirror which is supported on the frame and the free end of one member of said lever respectively so that it is tilted by a movement of the latter relatively to the frame, a fixed scale, and a telescope with a cross wire, substantially as 50 described.

5. In a trim indicator for ships, the combination of a framing, a weighted lever suspended in said framing, a mirror connected to and tilted by said lever, a fixed scale, and a telescope with cross wire, said scale and telescope being so disposed that an image of the scale can be seen in the mirror on looking through the telescope and the position of the cross wire on said image be observed, substantially as described.

6. In a trim indicator for ships, the combination of a framing, a weighted lever suspended on knife edges in said framing, a mirror supported partly by the frame and partly by the free end of one member of said lever, a fixed scale and a telescope with cross wire, said scale and telescope being so disposed that an image of the scale can be seen in the mirror when looking through the 70 telescope, substantially as described.

In testimony whereof I have signed my name to this specification in the presence of two subscribing witnesses.

RICHARD CADWALADR ROBERTS.
